Primary Examiner — Ricky Pham

(57) **CLAIM**

The ornamental design for an oven, as shown and described.

DESCRIPTION

FIG. 1 is a perspective view of an oven showing my new design;

FIG. 2 is a diagram of the open state of the oven;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 3;

FIG. 11 is an enlarged view of the encircled area 11 of FIG. 4; and,

FIG. 12 is an enlarged view of the encircled area 12 of FIG. 8.

The broken lines shown on the drawings depict portions of the oven that form no part of the claimed design. The dot-dash lines depict the enlarged view boundaries that do not form part of the claimed design.

1 Claim, 10 Drawing Sheets
